UNITED STATES PATENT OFFICE.

JOHN E. MINOR AND CARL M. PAGE, OF KANSAS CITY, MISSOURI, ASSIGNEES, BY
MESNE ASSIGNMENTS, TO THE UNIVERSAL SAFETY LOCK COMPANY, A CORPORA-
TION OF ILLINOIS.

LOCKING SYSTEM FOR AUTOMOBILES.

1,199,292.

Specification of Letters Patent. Patented Sept. 26, 1916.

Application filed December 17, 1913, Serial No. 807,291. Renewed February 25, 1916. Serial No. 80,553.

To all whom it may concern:

Be it known that we, JOHN E. MINOR and CARL M. PAGE, citizens of the United States, residing at Kansas City, in the county of Jackson and State of Missouri, have invented certain new and useful Improvements in Locking Systems for Automobiles, of which the following is a specification.

Our invention relates to a locking system for automobiles, and our object is to provide a new and useful system whereby unauthorized parties are prevented from starting an automobile during the absence of the owner.

The invention embraces a switch to control the ignition circuit of the automobile, and a combination lock to secure said switch in position to interrupt said circuit.

In order that said invention may be readily understood, reference will now be made to the accompanying drawings, in which:

Figure 1 is a diagrammatic view of a plurality of circuits controlled by our switch. Fig. 2 is an elevation of the combination lock and switch proper. Fig. 3 is an elevation of the combination lock and switch with the front part of the casing removed. Fig. 4 is a central vertical section on line IV—IV of Fig. 2. Fig. 5 is an irregular vertical section on line V—V of Fig. 4. Fig. 6 is a broken section on line VI—VI of Fig. 3. Fig. 7 is a vertical section of the switch on the plane of line IV—IV on Fig. 2. Fig. 8 is a detail of certain switch contacts for use in connection with a high tension magneto circuit.

Referring first to the combination lock and switch structure, 1 designates a casing embodying a removable back 2 upon which the switch and all the interior mechanism 40 of the lock is mounted, for convenience in assembling the various parts.

3 designates a centrally-disposed stationary stub-shaft projecting forwardly from the back plate 2.

4 and 5 designate two tumblers journaled upon the stub-shaft 3 and having oppositely-disposed marginal notches 6 and 7 for a purpose which will hereinafter appear.

8 designates a tumbler fixedly-mounted upon a knob 9 journaled in the front portion of the casing 1 and the stub shaft 3, Fig. 4. Tumbler 8 like the tumblers 4 and 5 has two oppositely disposed marginal notches 8^a and 8^b adapted to register with the notches 6 and 7 when the tumblers are properly manipulated.

Tumbler 4 is spaced from the back plate 2 by a spring washer 11. Tumbler 5 is spaced from tumbler 4 by a washer 12 and a spring washer 13; a washer 14 is interposed between tumblers 5 and 8.

Tumblers 4 and 8 have pins 15 and 16, respectively, projecting into the path of a pin 17 extending in opposite directions from the intermediate tumbler 5. The pins 15, 16, 65 and 17 coact in bringing the marginal notches of the tumblers into coincidence through proper manipulation of the knob 9, which is provided with a fixedly-mounted dial 18 that co-acts with a stationary pointer 19 on the front wall of the lock-case. The dial 18 and the pointer 19 act as guides in determining the proper manipulation of the knob 9 in solving the combination. In order that the combination can be readily changed, 75 we provide one or more of the tumblers with a series of holes 20, so that the pin or pins may be changed from one hole to another as desired.

21 designates a lever pivoted at one end 80 upon a post 22 within the lock and extending at its opposite end through a slot 23 in casing 1, the exposed end of the lever being provided with a handle 24. Lever 21 has an annular portion 25, so that it may be 85 swung to the right or left to actuate a primary switch member 26 without impinging against the central boss 1^a pressed in the front wall of the casing 1.

Switch member 26 is substantially U-shaped and pivotally mounted at one end 90 upon the post 22, it being spaced from the pivoted end of the lever 21 by a sleeve 27. The two arms of the switch member are provided with oppositely-disposed lugs 28—29; 95 lug 28 being adapted to enter the notches 6 and 8^a of the tumblers when the switch member is swung to the right and lug 29 being adapted to enter the notches 7 and 8^b of the tumblers when the switch member is 100 swung to the left.

The lower portions of the switch arms have two oppositely-disposed lugs 30 spaced a short distance apart to admit a flat spring 31 secured at its lower end by a pin 32 to a 105 lug 33 struck up from the lever 21. Spring 31 affords a yielding connection between the lever 21 and the switch member 26, whereby the latter may be swung to the right or left by the former without injury through violent or careless manipulation of the lever 21.

The lower portion of the switch member

26 is provided with a block of insulating material 34 provided with resilient contact fingers 35, 36 and 37.

The contact finger 35 is adapted to coact, in the present instance, with five ball-contacts 38, 39, 40, 41 and 42; contact finger 36 is adapted to coact with four ball-contacts 43, 44, 45 and 46; contact finger 37 is adapted to coact with ball contacts 47, 48, 49 and 50, to close certain circuits herein-after described.

Each ball contact is arranged in the tubular end of a binding-post 51 secured in a block of insulation 52 fixed to the back-plate 2 of the lock casing 1 by any suitable means, screws 53 being shown for that purpose. In addition to the binding posts 51 acting as electrical conductors they are also employed in securing the combination lock 20 and switch to any suitable portion of an automobile, such for instance, as the dashboard where it will be within convenient reach of the operator.

To insure perfect contact between the fingers and the balls the latter are pressed toward the former by springs 54, and the fingers are pushed toward the balls by springs 55 interposed between the lever 21 and the switch member 26.

30 When the switch is to be used in connection with a high-tension magneto, the contact fingers and balls are disposed as shown on Fig. 8.

Referring now to Fig. 1, which shows a plurality of circuits controlled by the switch, 77-78 designate electrically-controlled locks for securing the two sides of an automobile hood in closed position, so that access cannot be gained to the gasoline and ignition mechanisms housed beneath said hood. B designates the automobile motor; C the usual carburetor for supplying the motor B with gas charges; and D the customary low-tension magneto for controlling ignition of the gas charges. 102 designates an electrically-controlled valve whereby gasoline to the carburetor may be shut off at will, said valve having an inlet pipe E leading from a gasoline tank (not shown) 50 and an outlet pipe F leading to the carburetor C. The valve plug of valve 102 is adapted to be opened and closed by two solenoids, the first of which comprises a coil 106 and an armature 108, and the second a coil 142 and an armature 145.

The operation briefly stated is as follows: When the switch occupies the neutral position disclosed by Fig. 1, the valve 102 is held in closed position by a current passing from battery G through wire H, wire 129, contact 40, resilient finger 35, contact 32, wire 128, contact 140, sliding contact 103, on the valve stem 146, contact 141, solenoid

coil 142, line 107, and through line 69 back to battery G. The circuit for opening the valve is as follows: The switch member 26 is thrown to the right, permitting current from battery G to flow through line H, line 56, line 97, contact 39, resilient finger 35, contact 38, line 98, line 100, contact 101, 70 sliding contact 103, of the valve stem, contact 104, line 105, solenoid coil 106, line 107, and back to the battery G through line 69. The locks 77 and 78 of the automobile hood A are controlled by the following circuits: 75 Battery G, line H, line 56, line 71, contact 44, resilient finger 36, contact 43, line 72, line 74, push-button 79-80, contact 81-82, line 83-84, magnets 85-86, lines 87-88, lines 91-92, line 94, and back to battery G 80 through line 69. When the switch is thrown to the right as above described, a circuit to the magneto D is closed, which consists of line 69, battery G, line H, line 56, contact 48, resilient finger 37, contact 47, line 85 57, line 59, a secondary winding 109, and back to the magneto through line 111. When the motor B is running properly the circuit to the magneto through the battery G is cut out by shifting the switch 26 to 90 the extreme left position. This closes the magneto primary circuit through the winding 131, the spring contact 132, line 133, contact 50, resilient finger 37, contact 49, line 134, line 59, primary winding 61, line 64, 95 spring finger 67, grounds 68-135, and back to the armature winding 131.

Having thus described our invention, what we claim and desire to secure by Letters Patent is:

100

In a system of the character described, a U-shaped switch pivotally-mounted at one end and provided with lugs, a row of resilient finger contacts at the free end of said switch, two adjacent rows of stationary contacts near one end of the finger contacts arranged to be bridged by the latter when the switch is swung in one direction, two adjacent rows of stationary contacts near the opposite end of the finger contacts arranged to be bridged by the latter when the switch is swung in the opposite direction, circuits controlled by the contacts, tumblers disposed between the arms of the switch and provided with notches to receive the lugs 110 on the switch so that the latter may operate, and means to determine the position of said tumblers. 115

In testimony whereof we affix our signatures, in the presence of two witnesses.

JOHN E. MINOR.
CARL M. PAGE.
